DESIGN FOR A DISPENSER CABINET

Jay C. Perrin, Los Angeles, Calif.

Application November 9, 1936, Serial No. 65,810

Term of patent 7 years

To all whom it may concern:

Be it known that I, Jay C. Perrin, a citizen of the United States, residing at Los Angeles, in the county of Los Angeles and State of California, have invented a new, original, and ornamental Design for a Dispenser Cabinet, of which the following is a specification, reference being had to the accompanying drawing, forming part thereof.

Fig. 1 is a perspective view of a dispenser cabinet showing my new design.

Fig. 2 is a side elevation of said cabinet, and Fig. 3 is a front elevation of said cabinet.

I claim:

The ornamental design for a dispenser cabinet, as shown.

JAY C. PERRIN.
